(57) **CLAIM**

The ornamental design for a liquid perfume compact, as shown and described.

DESCRIPTION

FIG. 1 is a perspective view of a liquid perfume compact showing our new design.

FIG. 2 is a side elevational view thereof.

FIG. 3 is a top plan view thereof.

FIG. 4 is a bottom plan view thereof.

FIG. 5 is an exploded perspective view of a liquid perfume compact with its cap removed to show the applicator.

FIG. 6 is a perspective view of a second embodiment of the liquid perfume compact of FIG. 1;

FIG. 7 is a top plan view corresponding to FIG. 6.

FIG. 8 is a bottom plan view corresponding to FIG. 6.

FIG. 9 is a side elevational view corresponding to FIG. 6; and,

FIG. 10 is an exploded perspective view of the liquid perfume compact in FIG. 6 with its cap removed to show the applicator.

The broken lines shown in the drawings are for illustrative purposes only and form no part of the claimed design.
